UNITED STATES PATENT OFFICE.

CHARLES L. GOODRUM, OF NEW YORK, N. Y., ASSIGNOR TO WESTERN ELECTRIC COMPANY, INCORPORATED, OF NEW YORK, N. Y., A CORPORATION OF NEW YORK.

OVERFLOW RELEASE MEANS.

1,246,088.

Specification of Letters Patent. Patented Nov. 13, 1917.

Application filed April 27, 1916. Serial No. 93,870.

To all whom it may concern:

Be it known that I, CHARLES L. GOODRUM, a citizen of the United States, residing at New York, in the county of New York and 5 State of New York, have invented certain new and useful Improvements in Overflow Release Means, of which the following is a full, clear, concise, and exact description.

This invention relates to circuit arrangements for overflow release of line finder and selector switches.

One feature of this invention is the provision of means whereby the last line of a group, if it is not a selectable line, may be 15 used to release the finder switch whenever this switch goes to that position.

Another feature of this invention resides in the use of the last trunk contact for giving a busy signal when all the trunks of a 20 group are busy.

The drawing diagrammatically represents a portion of a telephone system employing the present invention.

The mechanism indicated within the 25 dotted line in the drawing is individual to a subscriber's line, and represents a line switch of the general character disclosed in Patent No. 1,151,543, of August 24, 1915, to A. E. Keith, "Telephone exchange trunking system." To the right of the dotted rectangle, there is diagrammatically indicated a first 30 selector switch, such as disclosed in applicant's application, Serial No. 41,587, filed July 23, 1915, "Automatic telephone exchange system," and circuits therefor having the present invention embodied therein.

The side switch indicated in the drawing may be similar in structure to that shown in Patent No. 815,176, March 13, 1906, Keith 40 and Erickson, "Automatic telephone connector switch," but differs therefrom in that in certain instances the wipers are moved upon the energization, instead of upon the deenergization, of the controlling magnet. 45 A side switch of this character is disclosed in the application of O. F. Forsberg, Serial No. 6302, filed February 5, 1915, "Telephone exchange switching mechanism."

It is believed that the invention will now 50 be clearly understood by tracing the operation of setting up a connection through the selector switch shown in the drawing.

Assuming that the subscriber, whose substation apparatus is indicated at the left in 55 the drawing, removes his receiver from the

hook, a circuit will be completed from battery through the left-hand winding of line relay 1, left-hand armature and back contact of cut-off relay 2, over the upper side of the line and through the substation apparatus, back over the lower side of the line, through the right-hand armature and back contact of cut-off relay 2, and through the right-hand winding of relay 1, back to battery. Relay 1 pulls up, and completes a circuit from grounded battery, through the right-hand winding of the plunger operating magnet 3, front contact and armature of relay 1 to ground. This magnet is energized and causes the operation of the plunger or contact operating device 4, by means of which the line spring terminals 19 and 20 are forced into engagement with the trunk terminals adjacent thereto.

In accordance with the well-known operation of a switch of this character, it will be understood that the plunger at the time of its operation was associated with a contact set in which an idle trunk terminated. Upon the closure of the line and trunk contacts, 80 a circuit is completed from grounded battery through the left-hand winding of the plunger operating magnet 3, cut-off relay 2, the lower line switch spring 20, relay 5, and back contact and armature of release magnet 6 to ground. Magnet 3 is maintained energized and relays 2 and 5 attract their armatures. Relay 5 at its inner armature grounds the trunk contact at the master switch, thus causing the idle plungers to move to a position before the next idle trunk, in a manner clearly explained in Patent No. 1,151,543 August 24, 1915, to A. E. Keith, "Telephone exchange trunking systems."

Simultaneously with the above, a circuit is 95 completed from grounded battery through stepping relay 7, side-switch wiper 17, upper spring 19 and trunk terminal of the line switch, front contact and left-hand armature of relay 2, over the subscriber's line 100 and through the substation circuits, back over the other side of the line, right-hand armature and front contact of relay 2, lower line switch spring 20 and relay 5 to ground. This interrupts the circuit for the release 105 magnet 6, which would otherwise be established from grounded battery, relay 6, outermost left-hand armature and front contact of relay 5, side-switch wiper 16, back contact and left-hand armature of slow release 110

relay 8, back contacts and armatures of relays 7 and 9 to ground. The energization of relay 7 completes a circuit from grounded battery through slow-release relay 8, front 5 contact and armature of relay 7, back contact and armature of test relay 9 to ground.

The subscriber now works his sending device to interrupt the circuit of relay 7. With the first deenergization of relay 7, the 10 rotary stepping magnet 10 and the slow-release relay 11 are energized in parallel by a circuit from battery through said relay and magnet with its controlling side-switch wiper in first position, in parallel, front 15 contact, left-hand armature of relay 8, back contact of relay 7 and back contact and armature of relay 9. The energization of slow-release relay 11, completes a circuit for escape magnet 12, which may be traced from 20 grounded battery, magnet 12, front contact and armature of relay 11 to ground. Relays 8 and 11 being slow to release, remain energized throughout the series of impulses. Each interruption of the line circuit and 25 consequent deenergization of stepping relay 7 causes the rotary magnet 10 to move the switch brushes over the group of trunks.

Upon the termination of the impulses, relay 7 remains energized, thus holding open 30 the circuit of relay 11, which falls off and opens the previously established circuit for the escape magnet 12, thus causing the side-switch wipers to move to their second position. In the present invention, as will be 35 described later, escape magnet 12 partakes of the functions of the test relay. Magnet 12 may therefore be regarded as a secondary test relay. In position 2 of the side switch, a circuit is established from battery through 40 the vertical stepping magnet 13, the individual interrupter 22 of said magnet, side-switch wiper 23, front contact and armature of relay 7, and back contact and armature of test relay 9 to ground. The terminals of 45 busy trunks traversed by the lower switch brush will be provided with raised potential so that the test relay 9 will not be energized. When, however, the switch brush engages the terminal of an idle trunk, which 50 will be connected to earth, relay 9 will pull up, interrupting the circuit for the stepping magnet 13 and completing a circuit from grounded battery through escape magnet 12, front contact and right-hand armature of 55 slow-release relay 8, and front contact and armature of relay 9 to ground.

In the device herein disclosed, a circuit is provided for the overflow release of the selector switch whenever all of the trunks of 60 the group are busy. This release means is equally effective for the release of any finder switch which has reached the last line of the group, if that line is not selectable.

The overflow release circuit of the selector 65 switch may be traced from grounded bat-

tery, relay 6, off-normal contact 15, back contact and armature of magnet 12, and grounded overflow contact 18, which is closed when the switch brush engages the last line of a group of busy lines.

As previously mentioned, the escape magnet 12 partakes of the functions of a test relay. When the test relay 9 is energized through a circuit completed by the switch brush engaging a grounded terminal, an 70 energizing circuit will be completed for escape magnet 12. This circuit may be traced from grounded battery, magnet 12, front contact, right-hand armature of relay 8, front contact and armature of relay 9 to 75 ground. When magnet 12 is energized it attracts its armature, thereby interrupting the circuit of the overflow releasing means. It should be noted that the magnet 12 is more active than magnet 6. By reason of 80 this provision, when the switch brush has seized the last idle trunk for use, magnet 12 prevents the overflow release means from acting, since magnet 12, by the attraction of its armature, interrupts the operating circuit for that releasing means. However, when the switch brush has encountered busy trunks in the group, magnet 12 will not be 85 energized, and its armature will remain in retracted position. In this case, when the 90 switch brush engages the last line of the group, the overflow contact 18 will be closed and the release mechanism actuated. It will readily be understood that the circuit herein described as the overflow release circuit 95 may be utilized in the transmission of busy signals, instead of effecting the release of the various automatic switches.

If the overflow release means has not been actuated, the escape magnet is energized and 100 moves the side-switch wipers to position 3 in a manner which is clearly disclosed in the applicant's application, Serial No. 872,743, filed November 18, 1914 "Automatic telephone exchange system."

As the operation of the switches succeeding the first selector may be of substantially the same character as that shown in applicant's application, Serial No. 35,326, filed June 21, 1915, "Two-wire multiple automatic telephone system," the operation of 115 establishing the rest of the connection will not be described.

Before the side switch moves to its third position, any deenergization of stepping relay 7 is momentary only and, therefore, relay 8 remains energized. This breaks the circuit from battery through release magnet 6, off-normal contact 15, and side-switch-wiper 16, which would otherwise be completed through the back contact and armature of relay 8, back contact and armature of relay 7, back contact and armature of relay 9. If the calling subscriber should interrupt his substation circuit while the series of im- 120 125 130

pulses were being sent, stepping relay 7 would fall off, causing the deenergization of relay 8 and the completion of the release circuit just described.

5 At the time the side switch moves out of position 2 and the stepping relay 7 becomes deenergized, relay 9 is energized (see Goodrum Serial No. 99,756, filed May 25, 1916, automatic telephone exchange systems, page 13 7, lines 1-8 inclusive), but when the side switch reaches its third position, relay 9 becomes deenergized, due to certain changes at the succeeding selector switch, thus opening up the release circuit which would otherwise be established from grounded battery through magnet 6, contact 15, wiper 16, back contact of relay 8, and front contact and armature of relay 9 to ground. At the termination of the conversation, relay 9 becomes 20 energized, due to circuit changes at the succeeding switch, in a manner which will be understood from the above mentioned application, Serial No. 35,826.

Should the subscriber, after the operation 25 of his line switch, replace his receiver on the hook without operating his sending device, the stepping relay 7 will become deenergized, and a circuit will be completed from grounded battery through the release 30 magnet, the outermost left-hand armature and contact of relay 5 and wiper 16 to ground, through the back contacts and armatures of relays 8, 7 and 9 as before.

The operation of magnet 6 interrupts the 35 circuit of relays 5 and 2 and magnet 3, and if the switch has moved from normal, magnet 6 establishes a holding circuit for itself, which is maintained through the off-normal contact 15 until the switch reaches normal 40 position.

The deenergization of magnet 3 allows the plunger 4 to be retracted. The retraction of the armatures of relay 2, connects the subscriber's line to his line relay 1, and the retraction of the armatures of relay 5 removes the busy potential from the trunk contact at the master controller, thus permitting the trunk to again be selected.

What is claimed is:

50 1. In a telephone system, a series of lines, a switch for interconnecting said lines, testing means for said lines at said switch, release means for said switch, a circuit including said release means, means for closing a 55 break point in said circuit when the switch contacts with the last of the series of lines, and means controlled by said testing means for positively opening another break point in said circuit when the switch engages the 60 last line of the series, if that line is idle.

2. In a telephone system, a series of lines having fixed contacts, a switch having movable contacts for engagement with said fixed contacts, testing means for said lines at said 65 switch, releasing means for said switch, a

circuit including the releasing means, two break points in said circuit, means for closing one of said break points when said movable switch contacts engage with the contacts of the last of the series of lines, 70 and means controlled by said testing means for positively opening the other break point when the switch engages the last line of the series, if that line is idle.

3. In a telephone system, a series of lines, 75 testing means for said lines, a switch for interconnecting said lines, releasing means for said switch, a circuit including a grounded contact and the releasing means, said circuit being grounded through said contact 80 when the switch engages with the last line of the series, and means controlled by said testing means for opening said circuit if the last line is idle.

4. In a telephone system, a series of lines, 85 a switch for interconnecting said lines, testing means for said lines at said switch, releasing means for said switch, a circuit including the release means and contacts, one of said contacts being normally open and 90 another of said contacts being normally closed, means for closing said normally open contact whenever the switch engages the last line of the series, and means controlled by said testing means for opening said 95 normally closed contact if the line engaged is idle.

5. In a telephone system, lines, a series 100 of fixed and movable contacts in which said lines terminate, automatic means for causing said movable contacts to engage said fixed contacts, test means for said lines, release means for said movable contacts, a contact actuated upon engagement of a movable contact with the last fixed contact of the series, 105 and a circuit for actuating said release means, said circuit being controlled at one point by the last mentioned contact and at another point by the said test means.

6. In a telephone system, a plurality of 110 lines, a series of fixed and movable contacts in which said lines terminate, means for causing said movable contacts to engage said fixed contacts, releasing means for said movable contacts, an overflow contact adapted 115 to be closed by the engagement of one of said movable contacts with the last fixed contact of the series, a circuit for controlling the releasing means including the overflow contact, and means for closing said 120 circuit under predetermined conditions by engagement of a movable contact with the last fixed contact.

7. In a telephone system, groups of incoming and outgoing lines, an automatic 125 switch having movable contacts in which said incoming lines terminate and fixed contacts in which said outgoing lines terminate, means for causing the movable contacts to engage the fixed contacts, an over- 130

flow contact adapted to be closed simultaneously with the engagement of a movable contact with the last fixed contact of the group, an escape magnet, an armature controlled by said magnet, and a circuit including the overflow contact and the armature of said escape magnet.

8. In a telephone system, a series of lines, a switch for interconnecting said lines,

means for operating said switch, a release magnet for said switch, a circuit for said magnet, and a contact arranged to close said circuit immediately upon the engagement of the switch with the last line of the series if that line is busy.

In witness whereof, I hereunto subscribe my name this 26th day of April A. D., 1916.

CHARLES L. GOODRUM.
